UNITED STATES PATENT OFFICE.

HARRY E. DOERR, OF ST. LOUIS, MISSOURI, ASSIGNOR TO SCULLIN STEEL CO., OF ST. LOUIS, MISSOURI, A CORPORATION OF MISSOURI.

PRESSED-STEEL SIDE FRAME.

Application filed April 5, 1924. Serial No. 704,314.

This invention relates to a new and improved pressed steel side frame and more particularly to a side frame having journal boxes secured thereto by welding, in such 5 manner as to become an integral part thereof.

Pressed steel side frames have heretofore been made and have been secured to journal boxes in various manners, as, for example, 10 by being bolted to a horizontal face of the frame. According to the present invention the journal box is fitted into an opening in the side frame and is thus secured against movement by the surrounding portion of the 15 side frame. It is welded to the side frame to secure it fixedly to the frame as an integral part thereof.

It is an object of the present invention to provide a side frame structure having 20 journal boxes integrally secured thereto and enclosed by a portion of the side frame.

It is a further object to provide a construction of this character in which the side frame is formed of a pair of members 25 welded together and in which the journal box extends through registering openings in the two side frame members and is welded to both said members.

Other and further objects will appear as 30 the description proceeds.

I have illustrated a preferred embodiment of my invention in the accompanying drawing, in which—

Figure 1 is a view of one-half of a side 35 frame constructed according to the present invention;

Figure 2 is a front view of Figure 1;

Figure 3 is a view of Figure 2 as seen from the left;

Figure 4 is a section taken on line 4—4 40 of Figure 2; and

Figure 5 is a section taken on line 5—5 of Figure 2.

The side frame as shown comprises two 45 pressed steel members 11 and 12, the inwardly extending flanges of which are welded together along the line 13. As shown in Figure 4, the side frame members are U-shaped in cross section through some 50 portions of their area, these U-shaped members being welded together. In such portions of the side frame as shown in detail in Figure 5, which is a section of the lower tension member, the side frame members

are L-shaped and are only secured together 55 by welding on a single line.

Each side frame member 11 and 12 has at each end an opening formed therein, the opening being surrounded by an inturned flange 14. As shown in Figure 3 these 60 flanges 14 and 15 abut on the line 13 and are welded together. These flanges are formed by drawing down the metal from the interior of the opening surrounded by the flange. 65

The lower flanges 11' and 12' shown welded together in Figure 5, are welded to the flanges 14 and 15 at 16 as indicated in Figure 2, to stiffen the construction. The journal boxes 17 which are preferably 70 formed of pressed steel are fitted into the opening encircled by the flanges 14 and 15. These journal boxes extend through upon both sides of the side frame and are welded to both of the members 11 and 12. They 75 thus aid in strengthening the connection between the two members and adding to the rigidity of the construction.

These journal boxes, as shown in Figure 3, have the hinge member 18 welded thereto and also the member 19 welded inside the box, this member serving to maintain the usual dust guard in position. 80

I have shown one preferred form of my invention by way of illustration but it is to 85 be understood that I contemplate such changes and modifications to meet varying conditions as are within the spirit and scope of the appended claims.

I claim:

1. Side frame construction comprising a side frame formed of pressed steel, an opening formed in the frame surrounded by a transversely extending flange, and a journal box fitted into the opening. 95

2. Side frame construction comprising a pair of pressed steel side frame members having inwardly extending flanges welded together, registering openings formed in the members, and a journal box extending through said openings and welded to the members. 100

3. Side frame construction comprising a pair of pressed steel side frame members having inwardly extending flanges welded together registering openings formed in the members surrounded by inwardly extending flanges, and a pressed steel journal box 105

fitted in said registering openings and bearing against the flanges.

4. Side frame construction comprising a pair of pressed steel side frame members having inwardly extending flanges welded together, registering openings formed in the members surrounded by inwardly extending

flanges, and a pressed steel journal box fitted in said registering openings and bearing against the flanges, said journal box being welded to both said frame members.

Signed at St. Louis, Missouri, this 2nd day of April, 1924.

HARRY E. DOERR.
